UNITED STATES PATENT OFFICE.

CHESTER J. McDONALD, OF SOUTH OMAHA, NEBRASKA.

COMBINATION-BRACKET FOR WINDOW SHADES AND CURTAINS.

No. 893,089.

Specification of Letters Patent.

Patented July 14, 1908.

Application filed December 20, 1907. Serial No. 407,425.

To all whom it may concern:

Be it known that I, CHESTER J. McDONALD, a citizen of the United States, residing at South Omaha, in the county of Douglas and State of Nebraska, have invented certain new and useful Improvements in Combination-Brackets for Window Shades and Curtains, of which the following is a specification.

This invention has for its principal object the provision of brackets, used in pairs, for the combined support of shade rollers and curtain rods upon window casings, said brackets being so formed that they may be reliable in operation, and may be more economically manufactured than heretofore presented.

Another object is the provision of brackets of this class which may be secured to a window frame without use of screws, and may be quickly adjusted or placed in operative position, and the invention has reference to the manner of forming the bracket.

The novel features of construction and arrangement of parts are fully described herein, pointed out by the claims and illustrated in the drawing, wherein,—

Figure 1 is a front view of part of a window frame with my invention operatively secured thereon, in connection with a window shade and curtain rod. Fig. 2 is a vertical, side view of the newly invented bracket operatively secured to a window frame, the latter being broken away and partly in section. Fig. 3 is an enlarged detail relating to Figs. 1 and 2.

Referring now to the drawing for a more particular description, numeral 1 indicates the front panel of a window frame, 2 and 3 indicating, respectively, a shade roller and a curtain rod, supported upon brackets 4, said brackets being secured upon the window frame. The two brackets are substantially alike in form and may be constructed of cast metal, but are preferably bent or formed from wire strands, and each bracket comprises the engaging-head 5, bent transversely from the neck 6 and provided near its terminal with side facets 7 disposed convergent toward terminal 8, and terminal 8 preferably has a sharpened point so that it may be driven into the window casing, and head 5 is provided with the hammer-facet 9 with a surface substantially at right angles with the elongated head, to facilitate the driving of

this head, as by use of a hammer, into the window frame.

The bracket may be conveniently and very economically bent upon a wire working machine, all of its parts after being completed, disposed upon a single plane. The strand is continued downwardly from neck 6 to form the sustaining-arm 10, this arm being curved or bowed outwardly at its middle so that it will not contact with and thereby define the window casing, during adjustment, and to form the contact-portion 11, and is then bent outwardly to form the shade-supporting arm 12, and is then bent downward as at 13 to form a part of the shade-bearing loop 14, and continued, as at 21, upwardly and substantially parallel with portion 13 to complete the shade-bearing loop; the strand is then bent outwardly and continued substantially parallel with arm 12, to form a curtain-pole supporting arm 15, and is then bent upwardly, as at 16, to form the terminal prong 17 for engagement with the curtain or drapery-pole.

As thus described the device may be constructed at slight expense, and when secured in operative position upon the window frame, the weight of the drapery, shade and roller is supported upon heads 5 of the brackets, as is apparent, and no other parts make contact with the frame except portions 11; and loops 14 are adapted to contain the projecting ends 18, whether round, square or oblong, of a shade roller. In order that heads 5 will reliably remain in the wood work after being driven, transverse contact-edges or ridges 19 are formed upon the sides thereof.

The brackets are secured very readily and conveniently by driving heads 5 into the window casing, facets 9 being especially useful to facilitate this operation. The brackets are spaced so that projections 18 of the shade-roller will rest in loops 14; a drapery-pole of the telescoping kind may be used to advantage and may be adjusted and held upon prongs 17, since the prongs traverse openings 20 thereof.

Having fully described my invention, what I claim as new and desire to secure by Letters Patent, is—

1. A device for the purpose described, comprising a metal strand having one of its terminals formed as a driving-head, and having a body-portion continued transversely downwardly from the driving-head to

105

110

form a sustaining-arm, the lower portion of said sustaining arm being adapted to bear against a window frame to brace the structure and bent outwardly at substantially a 5 right angle to form a shade-supporting arm, and from thence bent downward and thence upward to form a shade-bearing loop, said strand being continued outward from the shade-bearing loop substantially parallel 10 with said shade-supporting arm to form a curtain-supporting arm, and bent upwardly from the curtain-supporting arm to form a curtain-pole-bearing prong; said driving-head, sustaining-arm, shade-supporting arm, 15 curtain-pole supporting arm and curtain-pole-bearing prong disposed, substantially upon the same plane.

2. In a device of the character described an integral structure comprising a pointed,

inwardly and downwardly directed prong, 20 the side walls of which are serrated, a member extending downwardly from said prong there being a hammer facet formed at the juncture of said member and said prong, the strand forming the structure being bent outwardly from the lower portion of the downwardly extending member and then being bent to form a U-shaped member for the reception of the end of a shade roller, said strand being then bent outwardly to form a 25 horizontal arm and terminating in an upwardly extending prong.

In testimony whereof I have affixed my signature in presence of two witnesses.

CHESTER J. McDONALD.
